US0D1016782S

(12) **United States Design Patent** (10) **Patent No.:** **US D1,016,782 S**
(45) **Date of Patent:** **** Mar. 5, 2024**

(54) **EARPHONES**

(71) Applicant: **Apple Inc.**, Cupertino, CA (US)

(72) Inventors: **Christopher Wiita**, West Hollywood, CA (US); **Robert Boyd**, Los Angeles, CA (US); **Duy P. Le**, Los Angeles, CA (US); **Carlos M. Santana**, Granada Hills, CA (US)

2,545,731 A 3/1951 French
D168,240 S 11/1952 Rodriguez
2,739,660 A 3/1956 French
3,195,392 A 7/1965 Guy
3,213,679 A 10/1965 Lebow
3,301,253 A 1/1967 Glorig
D241,881 S 10/1976 Peterson et al.
4,457,396 A 7/1984 James
D278,234 S 4/1985 Saito

(Continued)

(73) Assignee: **Apple Inc.**, Cupertino, CA (US)

(**) Term: **15 Years**

(21) Appl. No.: **29/886,203**

(22) Filed: **Mar. 6, 2023**

(57) **CLAIM**

The ornamental design for earphones, as shown and described.

DESCRIPTION

FIG. 1 is a front view of earphones showing the claimed design;

FIG. 2 is a rear view thereof;

FIG. 3 is a top view thereof;

FIG. 4 is a bottom view thereof;

FIG. 5 is a right side view thereof; and,

FIG. 6 is a left side view thereof.

The broken lines in the figures show portions of the earphones that form no part of the claimed design.

1 Claim, 6 Drawing Sheets
